D12-128•

OR D 12,373 EX

SCHULNINGER

12373

UNITED STATES PATENT OFFICE.

A DOLPH SCHOENINGER, OF CHICAGO, ILLINOIS.

DESIGN FOR A CHILD'S CARRIAGE.

SPECIFICATION forming part of Design No. 12,373, dated July 26, 1881.

Application filed May 2, 1881. Term of patent 3½ years.

To all whom it may concern:

Be it known that I, ADOLPH SCHOENINGER, a citizen of the United States, residing at Chicago, in the county of Cook and State of Illinois, have invented and produced a new and original Design for Children's Carriages, of which the following is a specification, reference being had to the accompanying illustration, forming part thereof.

10 The illustration shows my carriage in perspective.

The design relates especially to the body and canopy-top of the carriage. The body is a box-frame, A, having panels B of perforated veneer. 15 The veneer panels are light in color, and are finished, preferably, in the natural color of the wood. The frame A is of dark-colored wood or painted some dark color. The contrast of the light perforated veneer panels and dark 20 frame gives a very pleasing effect. The body

has a rising back, arm-rails, and a dash-rail; but these are not essential features of the design. The top is a canopy-top, and is covered or formed of light-colored perforated veneer C, which contrasts nicely with the darker fringe 25 D around the edge of the top. The perforations in the body-panels, as well as the top, give the carriage a highly ornamental and finished appearance, and, in addition, make it look light and graceful.

30 I claim—

The design for a child's carriage shown and described, consisting of the body composed of box-frame A, of dark-colored wood, and perforated panels B, of light color, and the canopy-top C, of light-colored perforated veneer.

ADOLPH SCHOENINGER.
